Primary Examiner—Doris V. Coles**Attorney, Agent, or Firm**—Charles C. Corbin**[57]****CLAIM**

The ornamental design for a rod attached fish strike indicator, as shown and described.

DESCRIPTION

FIG. 1 is a front elevational view of a rod attached fish strike indicator showing my new design, the rear elevational view being a mirror image of said front view;
FIG. 2 is a side elevational view thereof;
FIG. 3 is a top plan view thereof;
FIG. 4 is a bottom plan view thereof; and,
FIG. 5 is a top, front perspective view thereof.
